UNITED STATES PATENT OFFICE.

OSCAR A. SMITH, OF CLEVELAND, OHIO, ASSIGNOR TO THE NATIONAL-ACME MANUFACTURING COMPANY, OF CLEVELAND, OHIO, A CORPORATION OF OHIO.

SELF-OPENING DIE.

1,085,762.

Specification of Letters Patent. Patented Feb. 3, 1914.

Application filed November 15, 1912. Serial No. 731,505.

To all whom it may concern:

Be it known that I, OSCAR A. SMITH, a citizen of the United States, residing at Cleveland, in the county of Cuyahoga and State of Ohio, have invented certain new and useful Improvements in Self-Opening Dies, of which the following is a specification.

This invention relates to improvements in threading dies of the character known as self-opening dies, the object of the invention being to provide a die which will allow a thread to be cut to the shortest length practicable in any desired pitch without the forward travel of the chasers when opening and which will insure the opening of the chasers instantaneously instead of gradually and thus avoid the making of a larger or tapered thread at the extreme end of the cut, and in which the die may be set or closed without any appreciable wear or friction on the cam or cam surfaces of the chasers or cutter blades.

A further object of the invention is the provision of a die having improved means for allowing an eccentric or floating movement of the body relatively to the casing and to obtain this without the use of springs.

In the drawings accompanying and forming part of this specification, Figure 1 is a perspective view of the improved die; Fig. 2 is a front end view thereof with the front cap partly removed; Fig. 3 is a cross-sectional view of the die with the chasers closed or set in their threading position; Fig. 4 is a view similar to that of Fig. 3, but illustrating the chaser operating cam member in that position which permits the chasers to open; Fig. 5 is a partly sectional perspective view of the front cap; Fig. 6 is a perspective view of the die body; Fig. 7 is a perspective view of the chaser operating cam member or disk; Fig. 8 is a perspective view of the die casing; Fig. 9 is a perspective view of the floating or eccentric compensating ring; Fig. 10 is a perspective view of the flanged shank or spindle by means of which the die is attached to the machine and also a view of the rear cap or ring for holding the floating ring shown in Fig. 9 and the flanged stem shown in Fig. 10 assembled; Fig. 11 is a perspective view of the die chaser and its guiding block or plate; Fig. 12 is a detail view of a part of the chaser operating cam member; Figs. 13 and

14 show different positions of the die chasers and the cam operating member in the operation of the die; Fig. 15 is a detail view of one of the screws used for holding certain parts of the die assembled; and Fig. 16 is a sectional view taken in line 16-16, Fig. 2.

Similar characters of reference indicate corresponding parts throughout the figures of the drawings.

The threading tool in the preferred embodiment thereof shown, comprises a die body 2 having a rearwardly extending hollow or cylindrical shank portion 3, and this die body is provided with a plurality of four guideways 4, 5, 6 and 7 extending radially thereof. The rear portions of these ways are grooved or undercut to form laterally extending recesses 8, and in each of the ways slides a die chaser or cutter 9, see Fig. 11, secured to a plate or block 9 which projects beyond the two side faces of the chaser and into its recesses 8. By means of this construction the chasers are guided in their opening and closing movements and are maintained against depthwise movement axially of the die. Each of these chaser guiding blocks 9 is provided with projecting pins 10 in position to engage coil springs 11 located in openings 12 of the die body on each side of the die chasers. These springs are effective to shift the chasers outwardly from the axis of the body. On one corner of the outer end of each of the plates 9 is formed a tapered cam projection 14 for the purpose hereinafter explained. Each plate 9 has a locating pin to fit in an opening 13 of its chaser. The outer end of each chaser is tapered circumferentially throughout the major portion thereof, that is, it is tapered transversely or at a right angle to the axis of the die, as at 28, but this tapered surface is straight axially, that is parallel with the axis of the die. In the rear of this tapered surface 28 the chaser is stepped, as at 28', a predetermined depth lower than the surface 28, and this surface 28' is also straight axially of the die, such stepped surface having a square shoulder.

For closing the die chasers suitable means is provided, herein designated as the die chaser operating means or member, or cam disk, and consists of an axially bored disk 16 having forwardly extending arms 17 squared on their outer ends or faces, as at

17', and each tapered along its inner edge, as at 18, for the major part of the length of each arm. The shank portion 3 of the die body extends through the bore of this 5 cam disk 16. Encircling this disk 16 and its forwardly extending arms 17 is the die casing 19, which is also centrally bored to receive the shank 3 of the die body. Over the front edge of this casing 19 and secured 10 to the die body is a front axially bored cap 20. For holding the die body, the chaser operating cam disk and casing 19 in proper assembled position relatively one to another, thereby to permit proper movement of the 15 chaser operating cam disk relatively to the chasers, the die body is provided with a pair of countersunk openings 21, the shoulders of which are engaged by the heads of screws 22, see Fig. 15, which project through the 20 openings 21. The inner end of each of the openings 21 of the die body is counter-bored to receive a washer 21' which rests against the shoulder 22' of this screw 22. These 25 screws 22 are threaded into the rear wall of the die casing 19 and hold the cam disk 16 against the rear wall of such casing 19, but allow the cam disk to rotate a fixed distance, by means of slots 16' provided in the disk 16, and through which slots 16' the 30 smoothed ends of the screws 22 project so that the disk 16 is prevented from movement axially of the die. In other words, when the screws 22 are turned into the rear wall of the casing 19 the distance from the 35 inner sides of the washers 21' to the threaded portions of the screws 22 is just enough longer to allow the cam disk to rotate while preventing movement thereof in the direction of the axis of the die.

40 For adjusting the chasers toward and from the work a suitable micrometer screw 31' is provided extending diagonally through the die casing 19 and held in any desired adjustment by a clamp washer and 45 screw 38' housed in the periphery of the casing 19. On the rear wall of the cam disk 16 is a stud or pin 31 so placed as to come into contact with the micrometer screw 31'. In the rear wall of the casing is milled an 50 elongated curved groove to receive this stud 31 and a coil spring 40. The pressure of the spring 40 against stud post 31 of the cam disk 16 forces this cam disk 16 against its adjusting screw 31', or in other words holds 55 the cam disk in whatever position it is adjusted to by the micrometer screw, that is to say, when the micrometer screw is operated it will turn the cam disk and so carry its stud 31 a predetermined distance in the 60 elongated groove and hold it there, so that when the cam disk is rotated away from the end of the micrometer screw and released it can return only as far as the end of the screw. A handle 30 passes through an elongated slot in the periphery of the casing 19 65 and is screwed into the cam operating disk 16. A pin 24' is fastened to the shank 3 of the die body 2 a suitable distance from the outer side of the rear wall of such body and the disk portion of the cam disk 16 has a recessed and tapered cam portion 24 in position to engage this pin 24' of the die body shank 3 at a predetermined time when the cam disk 16 is rotated.

70 To set the die the handle 30 is rotated to the right from the position shown in Fig. 13, thus bringing the tapered edges 18, see Fig. 7, of the arms 17 of the cam disk 16 into engagement with the projecting cam portions 14 of the chaser plates 9, which action forces 75 the chasers inward. By reason of the fact that the cam portions 14 of the plates 9 are relatively high, the movement of the chasers inward is sufficient to clear the outer ends or surfaces 28 of the chasers from the forward 80 ends of the arms 17, so that the chaser surfaces 28 by this movement of the cam disk are carried inward and therefore away from the forward ends of the arms 17 of the cam disk 16. This movement of the handle to 85 the right carries the cam disk 16 into position to bring the cam portion 24 thereof into contact with the pin 24' on the die body shank 3 and as this tapered cam portion 24 comes into contact with this pin 24' it will 90 of course draw back the die body and the chasers carried thereby into the casing 19 and so bring an extremely small portion of the rear edges 28 of the chasers under the extreme outer ends of the arms 17 of the cam 95 disk, whereupon, on releasing the handle, the spring 40 returns the cam disk automatically to its original position to which it has been adjusted by the micrometer screw. In Fig. 14 the full line position of the handle 30 and the arm 17 shows such arm 17 returning to its set position to the left, which 100 is indicated by the dotted position of the handle 30, during which returning movement, by reason of the fact that the die body 110 and the chasers have been drawn back in the manner just stated, the outer ends of the arms 17 merely shift circumferentially over the tops of the surfaces 28 of the chasers and hold them in their set position. As the 115 surfaces 28 are straight axially, that is parallel with the axis of the die, it follows that there is no tendency of the chasers to slip from under the ends of the arms 17. Thus it will be observed that as the cam disk 120 is rotated by its handle the tapered edges 18 thereof engage the surfaces 14 of the chaser plates and shift the chasers inwardly to such an extent that the surfaces 28 of the chasers are spaced from the extreme 125 outer ends of the cam disk arms 17 and during this movement the coöperation of the pin 24' and tapered cam surface 24 draws the die body with its chasers backward into the casing and thus draws the rear outer ends 130

of the chaser surfaces 28 under the extreme outer ends of the arms 17. In other words, when the tapered surfaces 18 of the arms 17 of the cam disk are shifted by means of the handle into engagement with the surfaces 14 the chasers are shifted toward the axis of the die to a greater extent than is necessary, so that when the die body is drawn back in the manner described the outer ends 10 or surfaces 28 of the chasers will be drawn under the extreme outer ends of the arms 17, the tapered surfaces 28 of such chaser outer ends controlling, in connection with the micrometer screw, the particular setting 15 of the chasers to cut the desired thread. When the shank 32 and the casing 19 to which it is attached has been arrested during its forward travel in the usual manner the continued forward travel of the die body 20 a very slight distance of course pulls the chaser surfaces 28 from under the extreme outer ends 17' of the arms 17 of the cam disk 16, so that without the further forward travel of the chasers themselves independently of the body, and by means of the straight stepped drop at the rear of the tapered surfaces 28 of the chasers, the chasers are instantaneously released from the forward ends of the arms 17. By operating 25 the micrometer screw out or in the cam disk is rotated forward or backward, thus adjusting the chasers to the desired depth of cut, as hereinbefore explained.

The floating or eccentric compensating 30 mechanism is constructed as follows: The rear of the casing 19 is bored to form a chamber to receive a disk 29, the diameter of which is machined to a predetermined size smaller than the bore of the casing. In 35 the edges of this disk are located four angular recesses 38 equally spaced. Fitted to slide in two oppositely located recesses are squared studs 37 carried by the wall of the chamber. The flange or disk of the stem 32 40 by means of which the die is secured in the machine or turret head also has two square studs 36 located in such position as to fit into the two remaining recesses of the disk 29. The diameter of the flange of this stem 45 32 is also machined smaller than the bore of the chamber a predetermined size. When these parts are assembled in the chamber or bore of the casing 19 they are held in place by a ring 34, which is bored to slip over the stem 32 and fastened to casing 19 by suitable 50 screws. The difference in diameter between the disk 29 and the flange of stem 32 and the diameter of the bore or chamber of the casing 19 determines the amount of eccentric or 55 floating movement the die will have, by reason of the fact that the pins fit loosely in the slots.

From the foregoing it will be observed 60 that the chasers are closed by rotating the chaser closing means instead of shifting it

axially, and that during this rotation of the chaser closing means the notch 24 comes into position to engage the pin 24', so that the inclined or tapered face of this notch 24 engages the pin and draws back the body 70 carrying the chasers and so brings the ends of the chasers under the ends of the forwardly projecting arms 17 of the cam disk and holds them in their set position, this being done without any appreciable friction 75 or wear on the ends of the chasers or cam for operating them. When the die has been properly fed forward until the usual stop, not shown, limits the further forward movement of the die casing and stem 32 the further pull on the chasers pulls the body forward an extremely small distance, releases the outer ends of the chasers from the ends of the projecting arms and allows them to open in the usual manner, without any forward movement of the chasers independently of the die body, so that the chasers will 80 instantaneously fly open. This is an advantage of extreme importance over that form of die where the ends of the arms 17 are tapered, or where the outer ends of the chasers are tapered in the direction of the axis of the die, for in such a construction the chasers had to be pulled continuously forward a sufficient distance to permit them 85 to be opened and there was therefore a gradual opening of the chasers, which had a tendency to cut a larger tapered thread at the extreme end of the threaded portion, whereas in the present case the chasers open 90 instantaneously and thus eliminate this disadvantage.

Among the advantages of the present construction are the following: That when the chasers are being set there is no wear on the 105 ends of the chasers, and the wear on the outer ends of the chasers or surfaces 28 and the ends of the arms when the die opens or releases is very slight compared with that wear which takes place in the setting of the 110 die chasers. Furthermore, the chasers having no forward movement themselves when opening, it follows that the die can cut very short threads, as the chasers practically instantaneously open. Further, the grooved 115 means for obtaining an eccentric compensating or floating movement is more universal and better, as it does not depend on springs for operating it. And further, the improved means shown effects a positive setting of the dies without the use of springs.

From the foregoing it will be seen that the die comprises a fixed part consisting of a stem 32 by means of which it is attached to the turret head, the casing 19 and the cam disk 16, which is fixed against axial movement although it has a rotatable movement to set the chasers but it is fixed, as stated, against any axial movement, and a movable part comprising the die body and the chas- 120

ers, the rear of which die body is in engagement with the front face of the cam disk 16 when the chasers are set and spaced therefrom, as shown in Fig. 4, when the chasers 5 are released.

I claim as my invention:

1. A threading die comprising a fixed part and a movable die body, shiftable thread cutting means carried by the body, and die setting means effective to shift the cutting means and including means effective to draw the die body toward the fixed part thereby to finally set the thread cutting means.
- 15 2. A threading die comprising a fixed part and a movable die body, shiftable thread cutting means carried by the body, and rotary die setting means effective on the rotation thereof to shift the cutting means and including positively acting means effective to draw the die body toward the fixed part thereby to finally set the thread cutting means.
- 25 3. A threading die comprising a fixed part and a movable die body, shiftable thread cutting means carried by the body, and die setting means effective to shift the cutting means and including cam formed means effective to draw the die body toward the fixed part thereby to finally set the thread cutting means.
- 35 4. A threading die comprising a fixed part and a movable die body, shiftable thread cutting means carried by the body, die setting means effective to shift the cutting means and including positively acting means carried by the die and effective to draw the body toward the fixed part, and means for bringing said positively acting means into engagement whereby the thread cutting means will be finally set on the drawing of the die body toward its fixed part.
- 45 5. A threading die comprising a fixed part and a movable die body, shiftable thread cutting means carried by the body, die setting means effective to shift the cutting means and including cam formed members effective to draw the die body toward the fixed part, and means for bringing said cam formed members into engagement whereby the thread cutting means will be finally set on the drawing of the die body toward the fixed part.
- 55 6. A threading die comprising a fixed part and a movable die body, shiftable thread cutting means carried by the body, and die setting means effective to shift the cutting means and including rotatable means carried by the fixed part and having means cooperating with a part of the body to draw said body toward the fixed part thereby to finally set the thread cutting means.
- 65 7. A threading die comprising a fixed part and a movable die body, shiftable thread cutting means carried by the body, and die set-

ting means effective to shift the cutting means and including rotatable means carried by the fixed part and having positively acting means coöperating with a part of the body to draw said body toward the fixed part thereby to finally set the thread cutting means.

8. A threading die comprising a fixed part and a movable die body, shiftable thread cutting means carried by the body, and die setting means effective to shift the cutting means and including rotatable means carried by the fixed part and carrying cam formed means coöperating with a part of the body thereby to draw the body toward the fixed part and finally set the thread cutting means.

9. A threading die comprising a fixed part, a body axially movable relatively thereto, shiftable thread cutting members carried by said body and each having a cam surface extending at an angle to the axis of the die and a stepped end having a part thereof parallel with the axis of the die, said cam surface projecting beyond said parallel surface, a rotatable member carried by said fixed part and effective to engage said cam surface and shift the cutting members inwardly, and positively acting means carried by the body and rotatable member whereby on the rotation of said member to shift the cutting members inwardly the die body will be drawn toward the fixed part thereby to bring the parallel surfaces of the cutting members under the rotatable member to set such cutting members.

10. A threading die comprising a casing, a body axially movable therein, shiftable thread cutting members carried by said body and each having a cam surface extending at an angle to the axis of the die and a stepped end having a part thereof parallel with the axis of the die, said cam surface projecting beyond said parallel surface, a rotatable member carried within the casing and effective to engage said cam surface and shift the cutting members inwardly, and positively acting means carried by the body and rotatable member whereby on the rotation of said member to shift the cutting members inwardly the die body will be drawn within the casing thereby to bring the parallel surfaces of the cutting members under the rotatable member to set such cutting members.

11. A threading die comprising a fixed part, a body axially movable relatively thereto, shiftable thread cutting members carried by said body and each having a cam surface extending at an angle to the axis of the die and a stepped end having a part thereof parallel with the axis of the die, said cam surface projecting beyond said parallel surface, a rotatable member carried by said fixed part and effective to engage said cam surface and shift the cutting members in-

- wardly, and positively acting means comprising a pin and a recessed cam surface carried by the body and rotatable member whereby on the rotation of said member to 5 shift the cutting members inwardly the die body will be drawn toward the fixed part thereby to bring the parallel surfaces of the cutting members under the rotatable member to set such cutting members.
- 10 12. A threading die comprising a casing, a die body, a plurality of chasers shiftably supported by said die body, each of said chasers having a surface tapered at right angles to the axis of the die and parallel 15 with the axis of the die and also having a stepped surface in the rear thereof and in the rear of said stepped surface a cam surface projecting beyond such parallel surface, and a rotatable member within the casing 20 having a plurality of parts each to engage one of said cam surfaces and shift the chasers toward the axis of the die and beyond their set positions, said rotatable member and body having means for then drawing 25 one of said parts toward the other to have the other of said parts of said rotatable member engage the parallel surfaces of the chasers.
13. A threading die comprising a casing, 30 a die body, a plurality of chasers shiftably supported by said die body, each of said chasers having a surface tapered at right angles to the axis of the die and parallel with the axis of the die and also having a 35 stepped surface in the rear thereof and in the rear of said stepped surface a cam surface projecting beyond said parallel surface, and a rotatable member within the casing having a plurality of forwardly projecting 40 arms corresponding in number with the number of chasers, each of said arms having a surface to engage one of said cam surfaces and shift the chasers toward the axis of the die and beyond their set positions, said rotatable 45 member and body having means for then drawing one of said parts toward the other to have the ends of said arms engage the parallel surfaces of the chasers.
14. A threading die including a body, 50 shiftable thread cutting members carried by said body, a rotatable member having a part coöperating with said thread cutting members and a part coöperating with said body, and means for rotating said member there- 55 by to shift the cutting members inwardly and then draw the same with the body and said rotatable member one axially toward the other and into engagement thereby to set the cutting members.
- 60 15. A threading die including an axially movable body, shiftable thread cutting members carried by said body, a rotatable member having a part coöperating with said thread cutting members and a positively act- 65 ing part coöperating with a part of said
- body, and means for rotating said member thereby to shift the cutting members inwardly and then draw the same with the body axially into engagement with said rotatable member thereby to set the cutting 70 members.
16. A threading die including an axially movable body, shiftable thread cutting members carried by said body and having a cam surface extending at an angle to the axis of 75 the body and a surface parallel with the axis of the body and beyond which said cam surface extends, a rotatable member having a part coöperating with said cam surface and a cam surface coöperating with a part of the body, and means for rotating said member thereby to shift the cutting members inwardly and then draw the same with the body axially to bring the parallel surfaces 80 of said cutting members into engagement with said rotatable member thereby to set the cutting members.
17. A threading die including an axially movable body, shiftable thread cutting members carried by said body, a rotatable member having a part coöperating with said thread cutting members and a part coöperating with said body, and means for rotating said member thereby to shift the cutting members inwardly beyond their set position 90 and simultaneously shifting the same with the body axially of the die and thereby effect engagement thereof with the cutting members on the return of such cutting members to their set position.
18. A threading die including an axially movable body, shiftable thread cutting members carried by said body, a rotatable member having a part coöperating with said thread cutting members and a part coöperating with said body, means for rotating said member thereby to shift the cutting members inwardly beyond their set position and simultaneously shifting the same with the body axially of the die and thereby effect 100 engagement thereof with the cutting members on the return of such cutting members to their set position, and means for adjusting the rotatable member circumferentially.
19. A threading die comprising a casing, 115 a die body, a plurality of chasers shiftably supported by said die body, each of said chasers having a surface tapered at right angles to the axis of the die and parallel with the axis of the die and also having a 120 stepped surface in the rear thereof and in the rear of said stepped surface a cam surface projecting beyond such parallel surface, a rotatable member within the casing having a plurality of parts each to engage one of 125 said cam surfaces and shift the chasers toward the axis of the die and beyond their set positions, said rotatable member and body having means for then drawing one of 130 said parts toward the other to have the other of said parts of said rotatable member engage the parallel surfaces of the chasers.

- parts of said rotatable member engage the parallel surfaces of the chasers, and means for adjusting the rotatable member circumferentially.
- 5 20. A chaser for a die, having a cam surface extending in one direction and a stepped surface having a portion extending at an angle to said cam surface and parallel with the axis of the die, the cam surface projecting beyond said parallel surface.
- 10 21. A chaser for a die, having a stepped end provided with a surface parallel with the axis of the die and also having a cam surface located at an angle to said parallel surface, one of said surfaces projecting beyond another.
- 15 22. A chaser for a die, having a broad guide plate provided with a cam surface, said chaser having a stepped end having a surface located at an angle to said cam surface and parallel with the axis of the die, one of said surfaces projecting beyond another.
- 20 23. A chaser for a die, having a broad guide plate provided with a cam surface, said chaser having a stepped end having a surface located at an angle to said cam surface and parallel with the axis of the die, said cam surface projecting beyond said parallel surface.
- 25 24. A chaser for a die, having a separable broad guide plate secured to the back thereof and provided with a cam surface, said chaser having a stepped end provided with a surface at an angle to said cam surface and parallel with the axis of the die, one of said surfaces projecting beyond another.
- 30 25. A chaser for a die, having a separable broad guide plate secured to the back thereof and provided with a cam surface, said chaser having a stepped end provided with a surface at an angle to said cam surface and parallel with the axis of the die, said cam surface extending beyond said parallel surface.
- 35 26. A chaser for a die, having a separable broad guide plate secured to the back thereof and provided with a cam surface, said chaser having a stepped end provided with a surface at an angle to said cam surface and parallel with the axis of the die, said cam surface extending beyond said parallel surface and said cam surface being located at one corner of said plate.
- 40 27. A chaser for a die, comprising a plate having at one corner a cam surface, the chaser having a surface located below and at an angle to said cam surface and parallel with the axis of the die.
- 45 28. A chaser for a die, having a guide plate provided with a cam surface at one corner thereof, the chaser having a stepped end provided with a surface located at an angle to said cam surface and parallel with the axis of the die, said cam surface project- 65 ing beyond said parallel surface.
29. A threading die comprising a body and a casing, said casing having a chamber at its rear and a pair of integral squared studs, a disk of smaller diameter than the bore of said casing and having a series of angular recesses a pair for the reception of said studs, a shank having a flange likewise of smaller diameter than the bore of the chamber and provided with a pair of integral squared studs for insertion into another pair of said angular recesses of the disk, and means for securing said parts together. 70
30. A threading die comprising a body and a casing, said casing having a chamber at its rear, a pair of disks located within said chamber and of predetermined smaller size than said chamber, said disks and chamber wall having coöperating angular recesses and integral squared studs, and means for 75 securing said parts together and supporting means carrying one of said disks. 80
31. A threading die comprising a body and a casing, said casing having a chamber at its rear, a pair of disks located within said chamber and of predetermined smaller size than said chamber, said disks and chamber wall having coöperating angular recesses and integral squared studs, all of the recesses being carried by one of said members 90 and the studs by the other two members, means for securing said parts together, and supporting means carrying one of said disks. 95
32. A threading die comprising a body and a casing, said casing having a chamber at its rear, a pair of disks located within said chamber and of predetermined smaller size than said chamber, said disks and chamber wall having coöperating angular recesses 100 and integral squared studs, all of the recesses being carried by that disk which is located between the chamber wall and the other disk and the studs being carried by the chamber wall and said other disk, the studs of the chamber wall being located in alternation 105 with the studs of said other disk, means for securing said parts together, and supporting means carrying one of said disks. 110
33. A threading die comprising a casing and a body, shiftable chasers carried by the body, a rotatable member carried by the casing for setting said chasers, a pin carried by the rotatable member, a spring carried by the casing for engaging one side of said pin, 115 and a micrometer screw for engaging the opposite side of and adjusting said pin and thereby adjusting said rotatable member to compress said spring, the spring holding the pin in engagement with the micrometer 120 screw. 125
34. A threading die comprising a casing and a body, shiftable chasers carried by the

body, a rotatable member carried by the casing for setting said chasers, a pin carried by the rotatable member, a coiled spring carried by the casing for engaging said pin, and 5 a micrometer screw for adjusting said pin and thereby said rotatable member to compress said spring, said pin extending rearwardly of said rotatable member and said casing having in its rear wall an elongated 10 curved slot for the reception of said spring and into which slot said pin projects.

35. A threading die comprising a fixed part and a movable die body, shiftable thread cutting means carried by the body, 15 rotary means effective to shift the thread cutting means toward the axis of the die, and means effective to draw the die body toward the fixed part thereby to hold the thread cutting means in its operative position.

20 36. A threading die comprising a fixed part and a movable die body, shiftable thread cutting means carried by the body, rotary means effective to shift the thread cutting means toward the axis of the die, and means 25 effective to draw the die body toward the fixed part thereby to hold the thread cutting means in its operative position, said rotary

means and thread cutting means having co-operating cam surfaces.

37. A threading die comprising a fixed 30 part and a movable die body, shiftable thread cutting means carried by the body, rotary means effective to shift the thread cutting means toward the axis of the die during the rotation thereof in one direction, and 35 means effective to draw the die body toward the fixed part during the rotation of said rotary means in the opposite direction thereby to hold the thread cutting means in its operative position. 40

38. A threading die comprising a die body, a casing for said body having a rear wall, a flanged spindle, and a coupling disk interposed between the spindle flange and the rear wall of said casing, said rear wall, 45 spindle flange and interposed disk having interlocking portions rotatably connecting them.

Signed at Cleveland, Ohio, this 12th day of November, 1912.

OSCAR A. SMITH.
